Primary Examiner — Leanne Was-Englehart*Assistant Examiner* — Yelizaveta Y Masalimova(74) *Attorney, Agent, or Firm* — Michael Best & Friedrich LLP(57) **CLAIM**

The ornamental design for a shoe, as shown and described.

DESCRIPTION

FIG. 1 is a perspective view of a shoe.

FIG. 2 is a first side view of the shoe shown in FIG. 1.

FIG. 3 is a second side view of the shoe shown in FIG. 1.

FIG. 4 is a top view of the shoe shown in FIG. 1.

FIG. 5 is a bottom view of the shoe shown in FIG. 1.

FIG. 6 is a front view of the shoe shown in FIG. 1; and, FIG. 7 is a rear view of the shoe shown in FIG. 1.

Broken lines are used to illustrate features of the shoe which form no part of the claimed design in the current numbered figures. For example, broken lines showing portions of the knobs, the tongue, the collar portion, the interior of the shoe, and the circular portions on the sole form no part of the claimed design in the current numbered figures.
